LAMP BULB-HEATED VAPORIZER OR SIMILAR ARTICLE

Harry J. Noel, 7922 Hillcrest Road, Indianapolis, Ind.

Filed Mar. 21, 1963, Ser. No. 74,070

Term of patent 14 years

(Cl. D16—2)

FIG. 1 is a perspective view of a lamp bulb-heated vaporizer or similar article showing my new design;

FIG. 2 is a side elevation thereof;

FIG. 3 is a side elevation of a modified form of the lamp bulb-heated vaporizer or similar article shown in FIG. 1 and differing therefrom only in the provision of a semi-circular recess in the lower side wall; and

FIG. 4 is a side elevation of the lamp bulb-heated vaporizer or similar article shown in FIG. 3 and rotated one-quarter turn from the showing in FIG. 3.

I claim:

The ornamental design for a lamp bulb-heated vaporizer or similar article, as shown and described.
